UNITED STATES PATENT OFFICE

2,181,263

GREASE SEPARATOR

George J. Dehn, Chicago, Ill.

Application February 16, 1937, Serial No. 126,013

6 Claims. (Cl. 210—56)

The invention relates to grease separators.

One object of the invention is to provide a grease separator with improved means for controlling or restraining the rate of flow of the drainage through the separator so that it will not flow in excess of the rate which is necessary efficiently to separate the grease from the other constituents of the drainage in transit through the basin of the separator. In separators heretofore devised by me embodying control for the rate of flow of drainage, as exemplified in Patent No. 2,003,140, the control device was located in the basin. This necessitated opening of the basin when it became necessary to change the rate of flow. One feature of the present invention consists in providing simple and efficient control means which is disposed outside of the basin where it will be readily accessible but only to inspectors or workmen who are authorized to make adjustments. By providing this control device outside of the basin, it becomes possible to attach it to a separator which has been installed, to increase the available space for the retention of grease in the basin, and to adjust the rate of flow without opening the separator basin.

A further object of the invention is to improve the separating efficiency of the separator and simplify the construction.

Other objects of the invention and the various advantages and characteristics of the present grease separator will be apparent from a consideration of the following detailed description.

The invention consists in the several novel features which are hereinafter set forth and are more particularly defined by claims at the conclusion hereof.

In the drawing which accompanies and forms a part of this specification or disclosure and in which like numerals of reference denote corresponding parts throughout the several views:

Fig. 1 is a sectional perspective of a grease separator embodying the invention;

Fig. 2 is a plan of the valve device for regulating or restricting the flow of the drainage to the basin of the separator;

Fig. 2^a is a vertical section of the device shown in Fig. 2;

Fig. 3 is a sectional view showing the container for the flow-restricting device, closed by a seal in lieu of by a lock, as illustrated in Fig. 1;

Fig. 4 is a sectional view illustrating the manner of supporting the horizontal baffles from the vertical bridge or partition in the basin; and

Fig. 5 is a vertical section taken on the line 5—5 of Fig. 1.

The separator which is shown in the drawing constitutes the preferred embodiment of the invention. It is adapted to separate grease from drainage and comprises a basin having an annular or cylindrical vertically extending wall 11 and an integral bottom 12. The top of the body is normally closed by a removable cover, which comprises an outer ring-like section 13 which is 10 removably secured by wing-nuts 16 and screws 17 within a projecting flange 15 and over a shoulder 15^a on the upper portion of the vertically extending wall 11 of the basin, and an inner plate-section 14 which covers a hand hole in, 15 and is supported by, the outer section 13, is fitted in a groove 18 and over a shoulder 18^a in the central portion of the outer section 13, and is removably secured in place by four wing-nuts 19 and screws 20 which are carried by the 20 outer-section 13. A packing-ring 15^b is fitted in a groove in shoulder 15^a and a packing-ring 18^b is fitted in a groove in shoulder 18 for sealing purposes. The inner section permits of ready access to, and removal of, the accumulation of 25 grease or matter in the upper portion of the basin. The removal of the outer or rim-section 13 permits of the removal of the hereinafter described baffles.

A reducing or flow retarding bushing 21 with 30 a large outer or inlet end and a small inner or outlet end is fixed or cast in a tubular extension 21^a which is located at one side of the basin and is formed as an integral part of the upper portion of the basin side wall 11. This bushing embodies at its large end, that is, its outer or inlet end, an internal screw thread whereby it is connected to a horizontal pipe section 32. In addition it embodies at its small or inner end an internal screw thread whereby it is connected to an inlet nipple 22 in the basin. The inner end of nipple 22 is screw threaded to an elbow 23 which is arranged so that one branch thereof extends downwards. A vertical pipe 24 is connected at its upper end by a screw thread 40 connection to the vertical branch or elbow 23 and serves to conduct the drainage to a point adjacent to the bottom 12 of the basin. At the opposite side of the basin a vertical discharge pipe 26 is provided. This pipe leads from a point 45 adjacent to the basin bottom to an elbow 27 and has its upper end connected by a screw thread to one branch of the elbow. The other branch of the elbow extends horizontally and is connected by a nipple 28 to a reduced shoulder- 50 55

formed opening in a tubular extension 29. The latter is positioned diametrically opposite the extension 21^a. It is formed as an integral part of the upper portion of the base and side wall 11 and is adapted to deliver the drainage after separation of the grease therefrom to a sewer by way of a pipe (not shown). By reason of the fact that the inner or inlet end of the bushing 21 and the shoulder-formed opening in the extension 29 are of a reduced or restricted diameter the flow of the drainage through the basin is retarded.

In grease-separators of this type, it has been found that the separating efficiency depends in great measure upon having the proper rate of flow or the flow properly restricted while the drainage is in transit through the basin so the grease will coagulate and coalesce before it reaches pipe 26 for discharge from the basin. To permit the rate of flow to be regulated for this purpose, a valve is provided outside of the basin for checking or regulating the rate of flow of the drainage through the inlet nipple 22 and pipe 24. This device comprises a vertically extending container or casing 30 with a tubular horizontal inlet 31 adjacent its upper end to which the drain pipe is suitably connected. The casing 30 is supported from the basin by the pipe-section 32 which, as previously pointed out, is threaded into the large outer end of the bushing 21. It is also supported by an elbow 33 which is threaded to pipe-section 32, and a vertical pipe-section 34 which is threaded into the up-turn of elbow 33. The upper portion of pipe-section 34 is threaded into the bottom of the casing 30. The valve for controlling the rate of flow of drainage to the separating basin comprises a rotatable valve-plate 35 which is provided with segmental openings 36 and a cap 37 provided with corresponding segmental openings 38 adapted to register in whole or in part with openings 36 to regulate the rate of flow of drainage through the valve. Plate 35 is rotatably suspended from the top of cap 37 by a stud 39 which is fixed in plate 35 and journaled in the top wall of cap 37. A wing-nut 40 is provided whereby the valve-plate may be securely clamped in its assigned position. The skirt of the cap 37 is screw-threaded to a vertical pipe-section 41 which is vertically aligned with the pipe-section 34 and removably connected thereto by a screw-threaded coupling-sleeve 42 which permits the removal of the pipe-section 41 for cleaning purposes. The drainage from inlet 31 is delivered into the chamber 43 in the casing 30, passes through the openings 36 and 38 in valve-members 35 and 37, and thence through the vertical pipe-connection between the valve and the pipe-section 34. The upper end of the casing 30 has screw-threaded therein a tight cap or cover 44. A suitable lock 45 has a rasp 45^a adapted to extend through lugs 46, 47 which are integral with and project from casing 30 and cover 40 respectively to prevent unauthorized access to the valve, so that the rate of flow of the drainage cannot be varied except by those skilled in separation. The drainage entering the inlet 31 flows over the cap 37 and through registering openings 36 and 38, the rate of flow being determined by the registering areas of the openings. The chamber in casing 30 around the pipe-section 41 and coupling 42 serves as an initial separating chamber for heavy matter before the drainage passes into the separating basin. A screw-plug 48 is provided in the bottom of casing 30 to permit the sediment or sludge in

the casing to be drained therefrom. This exemplifies a device which serves to control the rate of flow of the drainage to the basin of the grease-separator and is located on the outside of the basin so that it is accessible for setting only by authorized persons. This makes it possible to apply the control to grease-separators already installed. It makes it possible to vary the rate of flow without opening the separator-basin. It effects a saving of separating space in the basin. In practice, it is important that the rate of flow be established by a skilled engineer or plumber and, for that purpose, the lock 45 is applied to the cover 44 of the valve-casing 30. In Fig. 3 a seal 45^a and a suitable loop of metal 45^b, which is threaded through the lugs 46, 47, serves as a preventive against tinkering with the control device by unauthorized persons in lieu of a lock. This control device regulates the inflow of drainage to the separating basin and the rate of flow therethrough. In some instances, the character of the grease is such that a lower rate of flow is required than for others, and by adjusting the valve-plate 35, it becomes possible properly to restrict the flow for efficient separation of grease of different characters from the drainage.

To retard the flow of drainage through the basin and permit separation of the grease from the heavier matter or liquid, a vertical transverse partition 50 extends diametrically across the basin 11 midway between the vertical inlet pipe 24 and the vertical outlet pipe 26. The lower corners of partition 50 are confined between lugs 50^a on the basin to position the partition in the basin. A vertical series of spaced horizontal baffles 51 are supported from the partition 50 at one side thereof and a complementary series of baffles 52 are supported at the other side. Each of these baffles is provided with a pair of downwardly extending lugs or hooks 53, which fit in apertured ears 54 formed on the sides of partition 50 in order separately to support the horizontal baffles from the partition. The partition is adapted to be lifted out of the basin and hook and ear connections 53, 54 serve to lift the horizontal baffles with the cross-wall or baffle. Each baffle can be separately removed from the partition when the latter is removed from the basin. Each of the horizontal baffles 51, 52 is provided with an upstanding continuous marginal flange 55 or rim 56 which fits against the interior of the basin-wall and one side of the partition 50. The purpose of this flange is to cause the grease on the horizontal baffles to be retained thereon, while the baffle structure is lifted out of the basin for removal of the accumulated matter in cleaning the basin. In order to cause the drainage to traverse a sinuous path, the intermediate horizontal baffle 51 is provided with an opening 61 disposed at one side of pipe 24 through which the drainage passes and the uppermost baffle 51 is provided with an offset hole 62 at the opposite side of said pipe 24. Similarly, the uppermost baffle 52 on the discharge side of the opening is provided with an opening 63, and the intermediate baffle 52 is provided with an offset hole 64. In passing from one side of the partition 50 to the other, the drainage passes over the top of said partition. The upper end of partition 50 has short, horizontal, flow retarding baffles 65 projecting laterally therefrom. A handle 66 is fixed to upwardly extending lugs 67 on the partition 50 whereby the partition and the baffles supported thereby can be lifted out of the basin.

When there is an accumulation of grease in the

upper portion only of the basin, this can be readily removed when the inner cover-section 14 is released and removed from the outer cover-section 13. When it becomes necessary to remove the accumulation of material between the baffles, both cover-sections are removed and the nipples 22, 28 are unscrewed from the basin, whereupon the partition, vertical pipes 24, 26, elbows 23, 27, nipples 22 and 28 and all of the 10 baffles 51, 52 can be lifted out of the basin with all of the accumulated matter thereon.

A vent-pipe 68 is connected to the outer section 13 of the basin-cover so as to prevent the separator from becoming air bound or being 15 placed under pressure tending to force the accumulated grease separator from the basin. The inner cover-section 14 can be removed without disconnecting the vent.

The invention is not to be understood as restricted to the details set forth, since these may be modified within the scope of the appended claims, without departing from the spirit and scope of the invention.

Having thus described the invention, what I 25 claim as new and desire to secure by Letters Patent is:

1. In a grease separator of the character described, the combination of a basin provided with an inlet and an outlet for the circulation of 30 drainage therethrough, means in the basin for separating grease from the drainage as the latter circulates or flows through the basin, a casing outside of and above the basin adapted to receive the drainage prior to flow through the basin 35 and embodying an inlet for the drainage and a removable cover for providing access to the interior thereof, a pipe connection leading from the top portion of the casing interior through the casing to the basin inlet for conducting the 40 drainage from the casing to said basin inlet, and a valve for varying the rate of flow of the drainage through the pipe connection mounted within the upper portion of the casing on the casing end of the pipe connection and accessible for 45 regulating purposes upon removal of the cover.

2. In a grease separator of the character described, the combination of a basin provided with an inlet and an outlet for the circulation of drainage therethrough, means in the basin for 50 separating grease from the drainage as the latter circulates or flows through the basin, a casing outside of and above the basin adapted to receive the drainage prior to flow through the basin and embodying a laterally extending drainage inlet 55 in the upper portion thereof and in addition a removable cover for providing access to the basin interior and a plug closed opening in its bottom whereby any grease or other matter accumulating within the casing interior may be removed, 60 a pipe connection leading from the top portion of the casing interior through the casing bottom to the basin inlet for conducting the drainage from the casing to the said basin inlet, and a valve for varying the rate of flow of the drainage 65 through the pipe connection mounted within the upper portion of the casing on the casing end of the pipe connection and accessible for regulating purposes upon removal of the cover from said casing.

3. In a grease separator, the combination of a basin provided at the top portion thereof with

an inlet for drainage, a vertical partition extending across the lower portion of the basin, a downwardly extended pipe connected to receive the drainage from said inlet and discharge it downwardly in the basin at one side of the partition, a plurality of horizontal baffles at both sides of the partition fitting in the basin, and a vertical outlet conduit at the other side of the partition for conducting the drainage upwardly from said other side of the partition and through the baffles at said other side, the partition being removable from the basin and the horizontal baffles being removable with the partition and provided with upstanding longitudinal flanges for retaining matter thereon pending removal of the baffles from the basin. 5 10 15

4. In a grease separator, the combination of a cover closed basin provided with an inlet in the upper portion thereof for drainage, a vertical partition extending across the lower portion of the basin and mounted so that it is readily removable from the basin upon removal of the latter's cover, a downwardly extended pipe connected to receive the drainage from said inlet and discharge it downwardly in the basin at one side of the partition, horizontal baffles at said one side of the partition, a plurality of horizontal baffles between the other side of the partition and the basin, an outlet conduit at said other side of the partition, and detachable lug and hook connections between the horizontal baffles and the partition whereby the baffles are connected to the partition for conjoint removal therewith and are adapted upon removal of the partition to be moved from the latter by raising them 25 30 35 relatively thereto.

5. In a grease separator, the combination of a basin provided with an inlet at the upper portion thereof for drainage, a vertical partition extending across the lower portion of the basin, a downwardly extending pipe connected to receive the drainage from said inlet and discharge it downwardly in the basin at one side of the partition, horizontal baffles at one side of the partition and fitting in the basin, a plurality of horizontal baffles between the other side of the partition and the basin, an outlet conduit at the other side of the partition, and detachable lug and hook connections between the horizontal baffles and the partition, the partition being removably held in the basin and the baffles being provided with upstanding longitudinal flanges for retaining matter thereon pending removal of the baffles from the basin. 40 45 50

6. In a grease separator, the combination of a basin provided with an inlet for drainage, a vertical partition extending across the lower portion of, and removable from, the basin, a downwardly extending pipe connected to receive the drainage from said inlet and discharge it downwardly in the basin at one side of the partition, horizontal baffles between both sides of the partition and the basin, an upwardly extending outlet conduit at the other side of the partition, and short baffles formed integrally with and extending laterally in opposite directions from the upper end of the partition and projecting sufficiently beyond the sides of the partition so that they are positioned in overhanging relation with the inner portions of the horizontal baffles. 55 60 65 70
